United States Patent Office

Des. 216,675
Patented Mar. 3, 1970

216,675

BOTTLE

Keizo Saji, Kawanishi, Japan, assignor to Suntory
Kabushiki Kaisha, Osaka, Japan

Filed Jan. 24, 1969, Ser. No. 15,488

Claims priority, application Japan Sept. 24, 1968

Term of patent 14 years

D9—01

U.S. Cl. D9—56

FIG. 1

FIG. 2

FIG. 3

FIG. 1 is a front elevational view of a combined bottle and cap therefor showing my new design;

FIG. 2 is a rear elevational view;

FIG. 3 is an elevational view looking from the left of FIG. 1;

FIG. 4 is an elevational view looking from the right of FIG. 1;

FIG. 5 is a top plan view; and

FIG. 6 is a bottom plan view thereof.

The stippling indicates contrasting surface texture.

I claim:

The ornamental design for a bottle, substantially as shown and described.
